UNITED STATES PATENT OFFICE.

ARNOLD SCHÄRER, OF NEW YORK, N. Y.

MARCEL WAVER.

1,319,180.

Specification of Letters Patent. Patented Oct. 21, 1919.

Application filed November 15, 1917. Serial No. 202,236.

To all whom it may concern:

Be it known that I, ARNOLD SCHÄRER, a citizen of the Republic of Switzerland, and a resident of the city of New York, borough 5 of Manhattan, in the county and State of New York, have invented a new and Improved Marcel Waver, of which the following is a full, clear, and exact description.

Among the principal objects which the 10 present invention has in view are: To provide means for retaining the wave produced in hair; to provide means for waving hair without heating the same; to provide a device for accomplishing the above- 15 stated purposes, which is simple in form and easily cleansed and maintained sanitary; and to provide a device for accomplishing the purposes set forth, the parts whereof are adapted to yield to prevent 20 breakage when accommodating various thicknesses of strands of hair.

Drawings.

Figure 1 is a perspective view showing 25 several wavers of the character mentioned constructed and arranged in accordance with the present invention, and disclosed as when actively employed;

Fig. 2 is a perspective view of a waver 30 shown as in open position and in conjunction therewith a strand of hair disposed in position preliminary to closing the waver;

Fig. 3 is a detail in cross section showing the sides and blade of the waver and in 35 the closed position of the blade.

Description.

As seen in the drawings, the waver has a thin blade 9, which is pivotally connected 40 by means of a pin 10 to a handle 11. The handle 11 has resilient sides 12, which are separated to form the space 13, which normally the blade 9 substantially fills when closed or disposed therein as seen best in 45 Fig. 3 of the drawings. In its closed position, the blade 9 is held by small nibs 14 extended from the inner edges of the sides 12 adjacent the closed end of the handle

11. The nibs 14 register with and engage indents 15 in the free end of the blade 9. 50 The blade 9 and handle 11 of the waver are both preferably constructed of tortoise shell. It will be understood, however, that other materials may be substituted therefor.

When using the waver for making the 55 so-called "Marcel wave," the hair is drawn, as seen best in Fig. 2 of the drawings, to a strand, and the blade 9 is placed diagonally across the strand. When the sides 12 are closed, the sharpened edge of the blade 60 9 insures the production of a ridge in the strand of hair. When a second waver is placed on the same strand at the desired distance from the first, the blade 9 is introduced beneath the strand at a relatively opposite 65 angle.

When the wavers are disposed on the head, they are held in relatively parallel relation, such as shown in Fig. 1 of the drawings. The intermediate hair or hair 70 between the wavers, will be found to be bent in relatively curved layers producing the peculiarity of the so-called "Marcel wave."

The lock formed by the indents 15 and the nibs 14 is sufficiently positive to prevent 75 the separation of the blade 9 from the en-folding sides 12.

Claim.

A device as characterized comprising a 80 bifurcated handle; a thin blade member having a sharpened edge, said blade member approximately filling the space between the bifurcated members of said handle when in closed relation thereto, the sharpened 85 edge of said blade extending above the sides of said handle to form a sharp bending member for creasing hair held thereon by said handle; means for pivotally connecting the free ends of said handle with said blade; 90 and means for holding said blade in closed relation to said handle, said means embodying indents and corresponding projections integrally formed with said handle and said blade.

ARNOLD SCHÄRER.
